Inventor.

UNITED STATES PATENT OFFICE.

ELDRIDGE T. HILL, OF MURFREESBORO, TENNESSEE.

GATE-OPENER.

No. 830,434.

Specification of Letters Patent.

Patented Sept. 4, 1906.

Application filed June 15, 1906. Serial No. 321,934.

To all whom it may concern:

Be it known that I, ELDRIDGE T. HILL, a citizen of the United States, residing at Murfreesboro, in the county of Rutherford and State of Tennessee, have invented certain new and useful Improvements in Gate-Openers; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in devices for opening sliding gates, and comprises a swinging yoke carrying an antifriction-wheel which is designed to engage parallel rods positioned transversely upon the gate and against which the roller is adapted to bear as the yoke is raised and lowered, whereby the gate may be opened or closed.

The invention comprises various details of construction and combinations and arrangements of parts which will be hereinafter fully described and then specifically defined in the appended claim.

I illustrate my invention in the accompanying drawings, in which—

Figure 1 is a side elevation of my gate, showing the same in solid lines closed and in dotted lines opened; and Fig. 2 is a sectional view longitudinally through the gate, showing in top elevation the yoke.

Reference now being had to the details of the drawings by letter, A A designate posts between which a gate is adapted to slide, a suitable cross-piece A' connecting the lower ends of the posts, and which cross-piece is notched, as at A², forming a guide for the gate as it is opened and closed.

B B designate posts supporting a track B', upon which the grooved sheaves C, journaled at the upper ends of the end pieces D of the gate, travel. Fixed to the posts A is a cross-piece E, upon which the levers F are pivotally mounted, having ropes F' at their outer ends for convenience in tilting the levers.

The gate comprises a series of longitudinal strips H, fastened to the vertical pieces I,

and between the inner ends of said strips a space intervenes in which the parallel bars K are disposed, the ends of said bars being fastened to top and bottom strips J of the gate 55 and spaced apart.

N designates a yoke the rear end of which is pivotally mounted upon rods N', fixed to said posts A, and in the ends of the arms of said yokes is mounted a shaft O, which extends through the space intermediate said rods K, and R designates a grooved sheave journaled upon the shaft O and adapted to coact with one or the other of said rods K, accordingly as one or the other is frictionally 65 engaged by the sheave in the act of opening or closing the gate.

The inner ends of the levers F are pivotally connected together by means of a link F², and T T designate bars which are pivotally 70 connected each to one of said levers and their lower ends pivoted to the upper ends of the bars T², which are in turn pivotally connected to the arms of said yoke.

The operation of my gate will be readily 75 understood and is as follows: The gate being closed and should it be desired to open the same by a person approaching from either side thereof one or the other of the levers F may be tilted, causing the yoke N to 80 be raised, and as the sheave carried thereby bears frictionally against the rod nearest the rear end of the gate the latter will be caused to move backward as the yoke carrying the sheave rises toward a vertical position. A 85 reverse movement of one of the levers F will cause the yoke to be forced downward again, and as the sheave carried thereby frictionally engages the rod nearest the front end of the gate and a pressure applied thereto the gate 90 will move back into a closed position.

What I claim is—

A hand-opener for gates, comprising in combination with a sliding gate, bars connecting the top and bottom horizontal strips 95 thereof, and spaced apart, posts between which the gate is adapted to move, a yoke, having an arm of the latter disposed on either side of the gate, each arm being pivoted to one of said posts, a pivot-pin mounted in the other ends of said arms, a sheave journaled on said pin, and between said rods,

and against which the sheave is designed to contact, as the gate is opened or closed, pivotal operating-levers, link connections between the inner ends of the latter, a bar pivotally connected to each arm of the yoke, links, each connecting one of said bars, with an operating-lever, a cross-piece fixed to said posts, and having a recess formed in its

upper edge, in which the gate is guided, as set forth. 10

In testimony whereof I hereunto affix my signature in the presence of two witnesses.

ELDRIDGE T. HILL.
